UNITED STATES PATENT OFFICE.

WILLIAM AUTENRIETH, OF CINCINNATI, OHIO.

CRUTCH.

No. 869,128.

Specification of Letters Patent.

Patented Oct. 22, 1907.

Application filed July 13, 1907. Serial No. 383,653.

To all whom it may concern:

Be it known that I, WILLIAM AUTENRIETH, a citizen of the United States of America, and a resident of Cincinnati, in the county of Hamilton and State of Ohio, 5 have invented certain new and useful Improvements in Crutches, of which the following is a specification.

This invention has relation to crutches, especially to those of the convertible type and the object thereof is to provide a crutch of two superposed members 10 adapted to be adjustably and detachably held together, the upper member being an arm or crutch proper and the lower member being a hand or walking-cane.

One of the lesser or special objects of the invention 15 is to provide the upper or crutch member with a curved arm-piece having a detachable, suspended arm rest or pad therein.

Another lesser or special object of the invention is to provide a detachable handle for the lower or cane member 20 of the device, such handle also forming the grip for the hand when the two members are combined for assembled use as a crutch.

Other features of the invention will be fully herein-after described and particularly pointed out in the 25 claims.

In the accompanying sheet of drawings, Figure 1 is an elevation of my device showing the two members united for use as a complete crutch; Fig. 2, a view similar to Fig. 1, but on a somewhat larger scale, and showing 30 a part of the arm-piece in cross-section, a part of the body portion of the crutch-member in cross-section, a part of the upper portion of the cane-member in cross-section and the lower part of said cane-member in cross-section; Fig. 3, an elevation of the crutch-member shown detached and with the suspension arm-piece 35 pad removed; Fig. 4, an elevation of the cane-member detached; Fig. 5, an elevation of the cane-member showing its handle-portion detached and raised above its body portion; and Fig. 6, a sectional plan on dotted-line x, x , of Fig. 1, but on a larger scale.

In these views, 1 indicates the body portion or stick of the upper or crutch member, 2 the curved arm-piece at the upper end thereof, and 3, 3^a a short length of double tubing, the portion 3 of which latter is engaged by 45 the lower end of the body portion 1.

The body portion 1 and the arm-piece 2 are preferably made of an internal metal tubing 1^a and an external tubing 1^b of rubber or the like, a solid rod 1^c being suitably inserted and held in the metal tubing of said 50 body portion and such metal rod extending below the lower end of said body portion, as shown at 1^d in Figs. 1, 2 and 3.

4 is a T-shape hollow reinforce and coupling connecting the arm-piece to the upper end of the said body 55 portion.

5 represents a flexible pad having straps 6, 6 at its respective opposite ends; such straps being passed through loops or eyes in plates 7, 7, the latter being detachably secured to the opposite ends of the arm-piece by means of screws 8, 8. The ends of the straps 6, 6 60 are buckled together at 6^a, the tension of the pad being regulated and determined by the position of the draw-strap in the buckle, as is obvious. The pad is intended for initial use, or for sore and tender arm-pits, but ordinarily it is dispensed with and the plain curved 65 arm-piece; without the pad, as shown in Fig. 3, is used.

Thus far I have described in detail the crutch-member proper of my device and I will now take up the description in detail of the cane-member of my device, such cane-member being essential to the complement 70 of my device as a crutch, the said crutch-member being of no material use of itself.

9 represents the body portion or stick of the walking-cane member proper of my device, it forming the complement 75 of my convertible crutch when assembled with the crutch-member proper, as seen in Fig. 1, ready for crutch purposes.

10 represents a lateral arm, forming a handle at the upper end of the cane-member and, when in assembled position with the crutch-member, lying parallel, 80 but not in anywise adjacent, to the arm-piece and forming, also, the hand-grip of the crutch.

The cane-member is composed of an inner metal tubing 10^a and an external tubing 10^b of rubber or other suitable material, a metal rod 10^c extending from 85 the handle downward into the metal tubing or core of the body portion 9 and a metal rod 11 extending from the lower end of the inner tube of said body portion 9, all as best seen in Fig. 2.

A metal tubing or jacket 12 extends from the lower 90 end of the handle portion of the cane-member, its hollow extended end telescoping the upper end of the body portion 9, such upper end of the body portion 9 being slightly bent or deviated from a straight course at 12^a and passing upward through the member or barrel 3^a of the double tube at the lower end of the crutch-member. The upper end of the body portion 9 extends beyond the upper end of the barrel 3^a, about half the length of the jacket 12 and a set-screw 13 is used to detachably secure the handle-member to the body portion 100 of the cane-member.

Set-screws 14, 14 are used to attach the member 3 of the double tubing to the lower end of the body portion of the crutch-member, the other member 3^a of said double tubing practically forming a guide-way as well 105 as a means of connecting the body portion of the cane-member to the crutch-member. It will be seen that the jacket 12 and the set-screw 13, when secured in place, prevent the body portion 9 of the cane-member becoming detached from the member 3^a of the double 110

tubing that forms the coupling or union between the crutch and cane members.

To further connect and brace the crutch and cane members of my device, I place a short metal tubing 5 or sleeve 15 on the body portion 9 of the cane-member and secure it in the desired position thereon by means of a screw 16, and a lateral eye 17 is constructed on the side of said sleeve 15, such eye being engaged by the lower end of the extended portion 1^d of the internal rod 10 or core of the body portion 1 of the crutch-member. A firm and strong connection between the cane-member and the crutch-member of my device is thus produced in a practical and simple manner, and the device is readily converted for use as a crutch or a cane, the two 15 members forming the respective crutch and cane members of the device being readily separable and readily united as desired.

The position of the crutch-member on the cane member may be adjusted lengthwise, to suit slight 20 variations in the height of several users by simply supplying a series of screw-holes for the screws 13 and 16.

The lower end of the walking-stick is provided with the spur 18 which is part of the rod thereof and the usual rubber pad 19, with its tubular attaching-section 25 20 is screwed into place on the lower threaded end of the outer tubing of said cane-section. The spur 18 is for use on slippery surfaces, especially for winter use, but the rubber pad 19 and its tubular attaching-section

20 are first removed from place at the lower end of the cane-section.

In Fig. 1, I show how the device is made up when used as a crutch, with all the parts properly assembled, and in Fig. 4, I show the device as it appears as a cane and with all the parts of the crutch-member removed.

I claim:—

1. A convertible crutch comprising a crutch-member proper having an arm-piece at its upper end and a double tube coupling at its lower end, a cane-member having a detachable handle and with its body portion engaging one of the barrels or tubes of said double tube coupling of the 40 crutch-member and means for detachably uniting the said crutch-member and said cane-member.

2. A convertible crutch and cane comprising a crutch-member proper having a curved arm-piece at its upper end, a double tube coupling and an extension rod at its 45 lower end, a walking-cane member having a detachable handle and engaging one of the tubes of said double tube coupling at the lower end of said crutch-member, means for detachably uniting the crutch and cane members and a sliding sleeve on the cane-member engaging the extension 50 rod of the crutch-member.

3. A crutch comprising a body portion having a curved or concave arm-piece, a flexible pad having extended ends, adjustably connected together beneath the pad and loops detachably secured to the opposite ends of said arm-piece 55 and adapted to support the pad by its extended ends.

WILLIAM AUTENRIETH.
